TANK CAR UNLOADING APPARATUS

Chester A. Lewis, Cleveland, Ohio, assignor to
 C. A. Lewis, Inc., Cleveland, Ohio, a corpora-
 tion of Ohio

Application March 24, 1948, Serial No. 16,852

9 Claims. (Cl. 222—567)

1

This invention relates to devices and apparatus for making conduit connection with the discharge outlet of a tank, tank car, or the like, to withdraw or unload, and conduct away liquid contents from the tank.

The invention may be used to advantage with tanks in various art; but its advantages are most completely developed when it is used with railway tank cars and other tank vehicles. For this reason, I have chosen to illustrate and describe the invention herein as applied to a railway tank car.

Railway tank cars for transporting liquids although differing one from another in details, have some features in common. The tank proper has a short discharge outlet pipe projecting downwardly from its bottom, and a valve to open and close the pipe; and as a further precaution against leakage, the pipe is provided with a sealing closure cap threaded on the end of the pipe. The valve is constructed to close the inner end of the discharge pipe and is therefore inside the tank; and the handle for operating it is inside a dome at the top of the tank and accessible only after removing the cover of the dome.

Before filling the tank at the loading station, the valve is closed and the cap screwed on. At its unloading station, the cap is unscrewed and removed; and an unloading conduit which may comprise a hose or the like to conduct the liquid contents away from the tank, is screwed on to the pipe in place of the cap; and the pipe valve is then opened to discharge the liquid contents through the unloading conduit.

The discharge pipe is of large diameter; and because of the round shape of the tank at the bottom, must be located under the tank and approximately on its center line, that is, in the case of a railway tank car, not far from the ground and midway between the track rails. It is therefore inconvenient of access, and difficult to lift and screw onto it and unscrew from it a discharge hose connection of corresponding large size and weight.

Again, when a tank car has been emptied at an unloading station, and goes back to its loading station to be filled again, the cap may have already been replaced at the unloading station, or if not, will be replaced at the loading station because its absence can be visibly detected.

The valve is also supposed to be closed before refilling begins, but in some instances this is neglected and the valve is left open, the closure cap preventing leakage or making it so slight as not to indicate that the valve is not closed.

2

In other instances, the attendant may attempt to close the valve and believe that he has done so, but because of some obstructing material or object in the tank the valve may be held open.

When the tank car in such case reaches its unloading destination again, and the operator takes off the closure cap, and the valve being open as stated, the contents of the tank rushes out, and makes it difficult and almost impossible for the operator to screw on the unloading connection. This waste flow can ultimately be stopped by closing the discharge pipe valve but in the meantime and because of the inaccessibility of the valve handle a considerable part of the tank contents is lost.

Again and sometimes of even greater importance, the contents of the tank may be of such nature as to be corrosive, or highly acid, or volatile, and the operator may be injured by the uncontrolled waste flow from the outlet pipe by its coming in contact with exposed parts of his body, or by his inhaling vapors from it, etc., and in such cases there is not only the matter of compensation for injury, but also because of the shock of unexpectedly being subjected to danger, the operator's attention will be directed to saving himself, and he will give no thought to closing the valve to stop the waste.

It is to prevent this inconvenience, waste, loss, and casualty liability, that the present invention has been made.

The invention comprises generally speaking, an apparatus mounted to run on ground wheels in the nature of a vehicle, and to be propelled by a handle. It comprises an unloading conduit, and a pressure-seal connection therefor which can be raised and lowered by manipulating the handle.

After removal of the closure cap from the tank discharge pipe, the vehicle can be moved by the handle to dispose the pressure-seal connection directly under the discharge pipe, and it can then be raised to seal the unloading conduit upon the discharge pipe, by depressing the handle. Thereafter the flow of the tank contents into the unloading conduit may be controlled by the discharge pipe valve, or by a manual valve provided on the vehicle.

The objects of the invention are to provide a device or apparatus by the use of which the inconvenience, loss of time, loss of material, danger to workmen, etc. referred to hereinbefore may be avoided.

Other objects will be apparent to those skilled in this art, among which may be mentioned the

provision of an improved conduit connection which will effect a sealed juncture with the end of a pipe such as the discharge pipe of a tank by raising it into pressure engagement with the end of the pipe; and the provision of a vehicle or carriage mounting such connection so that it may be positioned for operation by movement of the vehicle as a whole by a propelling handle, and operated by lowering the handle.

The invention is fully disclosed in the following description taken in connection with the accompanying drawing, in which:

Fig. 1 is a side elevational view of a structure embodying the invention, showing in association therewith and in end elevation a part of a railway tank car;

Fig. 2 is a top plan view of the structure of Fig. 1, without the car and its associated parts;

Fig. 3 is a view similar to Fig. 1, but with parts of the structure in different operative positions;

Fig. 4 is a fragmentary sectional view from the plane 4—4 of Fig. 1.

Referring to the drawing, Figs. 1 and 3, there is indicated in simplified form at 1 a railway tank car, comprising: a tank 2; a frame 3, including a platform or plank cat-walk 4, upon which attendants may walk around the tank; the wheels and undercarriage of the car having been omitted for simplification; but the car is further identified by the showing of the track rails at 5—5.

From the underside of the tank 2 depends a discharge pipe 6. The valve controlling the pipe 6 is indicated in broken lines at 7 and a stem 8, fragmentarily shown, connects the valve to a handle at the top of the tank as referred to above.

As shown in Fig. 3, the lower end of the pipe 6 is closed by a sealing closure in the form of a cap 9 threaded on to the end of the pipe.

In general, this is the construction of the type of railway tank car with which the invention is adapted to be used, in unloading the contents of the tank through the discharge pipe 6 and conducting it away.

The structure embodying the invention is in the form of a vehicle comprising a pair of spaced apart ground wheels 10—10, rotatable on an axle 11, and supporting a frame shown generally at 12.

The frame 12, preferably, has two spaced apart side bars, of angle section steel, comprising horizontal front end portions 13—13; body portions 14—14 depending rearwardly therefrom, to and beyond the wheels 10—10; and there, as at 15 (Fig. 1) bent to incline upwardly rearwardly and also to converge inwardly, at portions 16—16, meeting at parallel rear end portions 17—17, welded together at 18.

The wheel axle 11 is mounted upon the frame portions 14—14 in any suitable manner.

The frame 12 is braced by a transverse brace 19 welded to and connecting the side portions 14—14, and by a brace 20 welded to and connecting the side portions 16—16.

At the forward end of the frame, a plate 21 spans the side portions 13—13 and is welded thereto (see particularly Fig. 4), and serves as a frame brace, but also serves as a base and guide for supporting and guiding movements of a pressure-seal connection to be described.

At the rear of the frame, the side bar portions 17—17 being of angle section and welded together at confronting flange-edges as shown at 18, provide a channel in which one end of a length of steel tube 22 is laid and welded as at 23, and constitutes a vehicle tongue, continuing in the direction of the side bar portions 16—16.

At the outer end of the tongue 22 is an elongated tubular handle shank 24, extending rearwardly and downwardly and terminating in a transverse handle 25.

To mount the handle shank 24 on the end of the tongue 22, a pair of parallel side plates 26—26 are welded to the opposite sides of the tongue 22, and the handle shank 24 is placed between them and removable bolts 27—27 are projected through aligned holes in the side plates and shank.

The inside and outside diameters of the vehicle tongue 22 and of the handle shank 24 are preferably sized so that the shank 24 after detaching it by removing the bolts 27—27 can be telescoped into the tongue so as to take up less room when being transported or stored out of use.

A tool box 28 is mounted upon transverse angle-bars 29—30 joining the side bar portions 16—16 and 14—14 respectively and these angle bars may also serve to further brace the frame.

At the forward end of the carriage, an unloading conduit is provided comprising a short length of pipe 31, extending upwardly through a perforation 32 in the aforesaid plate 21, see Fig. 4, and communicating at its upper end with the interior of a generally bowl-shaped upwardly open receptacle 33 the bottom 34 of which is welded upon the upper end of the pipe 31.

Supported on the bowl bottom is a plurality of washer-like annular rubber sealing gaskets 35—35 in a tier, surrounding the open end of the pipe 31 and held concentric therewith by fitting at their outer peripheries the inner wall 36 of the receptacle bowl 33.

Below the plate 21, the pipe 31 is connected to a valve 36 having an operating handle 37 and below the valve 36 is a pipe elbow 38 connected to a generally horizontal pipe 39, which at its outer end is threaded as at 40 to receive the coupling of a hose.

The receptacle 33, pipe 31, valve 36, elbow 38, and pipe 39 are all assembled together as a unit, and a spring 41, reacting at its opposite ends upon the underside of the bowl receptacle 33 and upon the upper side of the plate 21 and surrounding the pipe 31, yieldingly supports the unitary assembly on the plate 21.

The pipe 31 is positioned by the perforation 32 in the plate 21 through which it extends, and is at a predetermined distance forwardly from the wheels 10—10 to be referred to. The perforation 32 is larger than the pipe 31 so that the pipe 31 and the other parts assembled with it can rock or oscillate on the plate 21 supporting them.

The whole assembly can also rotate in the perforation 32, and the pipe 39 is preferably of such length that it can be rotated rearwardly and lie under the carriage frame portions 14—14 forwardly of the wheels 10—10 during transportation or for storage when not in use.

The opening at the upper end of the pipe 31 and through the center holes of the annular gaskets 35 into the receptacle 33 is smaller than the opening at the lower end of the discharge pipe 6 on the car as commonly provided.

In the operation of the device above described, it is assumed that the loaded tank car arriving at an unloading station has the sealing cap 9 in place and the valve 7 closed.

The operator propels the vehicle to the vicinity of the car by pulling or pushing on the handle 24—25. He then rotates the pipe 39 from under the frame portions 14—14 so that it projects

forwardly from the vehicle, and pushes the forward end of the vehicle under the car tank to place the receptacle 33 approximately at the center line of the car and near the tank discharge pipe 6; and this position can be gaged by constructing the vehicle so that the distance from the wheels 10-10 to the perforation 32 in the plate 21 as referred to is slightly greater than one-half the distance between the rails 5-5, and by moving the wheels up into engagement with one of the rails. The operator can then release the handle and this allows the parts forwardly of the wheels 10-10 to rock downwardly until the pipe 39, rests upon the opposite rail 5, and allows the handle to rise.

This disposes the parts generally as shown in Fig. 3. A hose can now be coupled to the end of the pipe 39 as referred to.

The cap 9 is now removed from the discharge pipe 6, and the vehicle is maneuvered by the handle 24-25 to bring the receptacle 33 directly under the end of the discharge pipe 6; and then the handle 24-25 is depressed, raising the plate 21 and the assembly thereon. This causes the end of the pipe 6 to enter the receptacle, the side wall of the receptacle being flared outwardly as shown to guide the pipe 6 into it; and causes the gaskets 35-35 to be pressed into engagement with the end of the pipe 6 and compresses the spring 41 to effect a pressure seal; the parts then taking up the position shown in Fig. 1.

The valve 36 at this time may be closed. The valve 7 is now opened and when it is observed that the spring pressure and rubber gaskets have made a leakproof seal at the end of the pipe 6, the valve 36 is opened and the tank contents flow from the tank through the pipes 31 and 39 and through the said hose (not shown) at a rate which can be controlled either by the valve 7 or the valve 36.

Provision is made to hold the handle 24-25 in the depressed position, against the reaction of the spring 41 tending to rock the carriage and raise the handle, to relieve the operator for other work, as shown in Fig. 1.

A U-shaped sheet metal clip 42 is made to slip over the edge of the catwalk plank or like platform 4; a depending ratchet bar 43 is loosely hinged to the underside thereof as at 44; and the bar 43 is provided with a series of ratchet teeth 46, on its forward side preferably inclined downwardly forwardly.

The aforesaid angle iron brace 20 has one of its flanges 47 upwardly rearwardly inclined; and the brace 20 is so disposed on the frame that when the wheels 10-10 are in their working position (which as mentioned is approximately in engagement with one of the rails 5 as shown in Fig. 1), the ratchet bar 43 will rest by gravity against the brace flange 47.

As the handle 24-25 is depressed lowering the brace 20, the edge of the flange 47 ratchets over the teeth 46. Upon releasing the handle, the carriage tends to be rocked in the reverse direction on the wheels 10-10 by the reaction of the spring 41 and this projects the flange 47 under the nearest ratchet tooth 46 and the carriage is thereby stopped against further rocking by the ratchet bar 43.

To mount the ratchet bar 43 as described, a preferred way is to first insert the lower end of the bar through the frame rearwardly of the brace 20, and then put the clip 42 in place.

When the tank, ready to be unloaded, has

the sealing cap 9 in place, but the valve 7 accidentally open, the tank contents will flow out of the pipe 6 immediately when the cap is removed, and be wasted with the loss and hazard mentioned hereinbefore.

However, at this time, as described above, the vehicle has already been positioned as shown in Fig. 3, with the receptacle 33 adjacent to the discharge pipe 6, and in such event the handle 10 24-25 can be manipulated to quickly swing the receptacle under the pipe 6 and then raise it to seal off the end of the pipe 6 as described and stop the flow, placing it under control of the valve 36 of the device.

15 The vehicle as illustrated may be variously changed and modified as to the exact details of its construction, as will occur to those skilled in the art; and the invention comprehends all such changes and modifications which come 20 within the scope of the appended claims.

I claim:

1. In a device for sealingly connecting an unloading conduit to the depending discharge pipe of a tank car or the like; a vehicle comprising a 25 vehicle frame supported on wheels on a transverse axis and comprising frame portions forwardly and rearwardly of the axis; unloading conduit means comprising a generally upright upwardly open conduit mounted on the forward portion of the frame for limited downward yielding movement, by spring means reacting thereon and on the frame; gasket means surrounding the open upper end of the conduit and means supporting the gasket means in sealing relation to the conduit upper end; the conduit having a lateral extension below its upper end; the forward frame portion being rockable upwardly around the wheel axis to elevate the conduit and yielding press the gasket means into sealing engagement with the end of the car discharge pipe upon depression of the rearward portion of the frame.

2. In a device for sealingly connecting an unloading conduit to the depending discharge pipe of a tank car or the like; a vehicle comprising a 45 vehicle frame supported on wheels on a transverse axis and comprising frame portions forwardly and rearwardly of the axis; unloading conduit means comprising a generally upright upwardly open conduit mounted on the forward portion of the frame for limited universal movement relative thereto and supported thereon for downward yielding movement, by spring means reacting thereon and on the frame; gasket means surrounding the open upper end of the conduit

50 and means supporting the gasket means in sealing relation to the conduit upper end; the conduit having a lateral extension below its upper end; handle means on the rearward portion of the vehicle frame for propelling the vehicle for maneuvering it on its wheels, to dispose the conduit and gasket means under the car discharge pipe; the forward frame portion being rockable upwardly around the wheel axis to elevate the conduit and yielding press the gasket means into sealing engagement with the end of the car discharge pipe upon depression of the rearward portion of the frame.

55 3. In a device for sealingly connecting an unloading conduit to the depending discharge pipe of a tank car or the like; a vehicle comprising a vehicle frame supported on wheels on a transverse axis and comprising frame portions forwardly and rearwardly of the axis; unloading conduit means comprising a generally upright upwardly open conduit mounted on the forward

70 portion of the frame for limited downward yielding movement, by spring means reacting thereon and on the frame; gasket means surrounding the open upper end of the conduit and means supporting the gasket means in sealing relation to the conduit upper end; the conduit having a lateral extension below its upper end; handle means on the rearward portion of the vehicle frame for propelling the vehicle for maneuvering it on its wheels, to dispose the conduit and gasket means under the car discharge pipe; the forward frame portion being rockable upwardly around the wheel axis to elevate the conduit and yielding press the gasket means into sealing engagement with the end of the car discharge pipe upon depression of the rearward portion of the frame.

75

portion of the frame for limited downward yielding movement, by spring means reacting thereon and on the frame; gasket means surrounding the open upper end of the conduit and means supporting the gasket means in sealing relation to the conduit upper end; the conduit having a lateral extension below its upper end; the forward frame portion being rockable upwardly around the wheel axis to elevate the conduit and yieldingly press the gasket means into sealing engagement with the end of the car discharge pipe upon depression of the rearward portion of the frame; and strut means associated with the vehicle and with a portion of the car above the rearward frame portion to retain the same depressed.

4. In a device for sealingly connecting an unloading conduit to the depending discharge pipe of a tank car or the like; a vehicle comprising a vehicle frame supported on wheels on a transverse axis and comprising frame portions forwardly and rearwardly of the axis; unloading conduit means comprising a generally upright upwardly open conduit mounted on the forward portion of the frame for limited universal movement relative thereto and supported thereon for downward yielding movement, by spring means reacting thereon and on the frame; gasket means surrounding the open upper end of the conduit and means supporting the gasket means in sealing relation to the conduit upper end; the conduit having a lateral extension below its upper end; handle means on the rearward portion of the vehicle frame for propelling the vehicle for maneuvering it on its wheels, to dispose the conduit and gasket means under the car discharge pipe; the forward frame portion being rockable upwardly around the wheel axis to elevate the conduit and yieldingly press the gasket means into sealing engagement with the end of the car discharge pipe upon depression of the rearward portion of the frame; and strut means associated with the vehicle and with a portion of the car above the rearward frame portion to retain the same depressed.

5. In a device for sealingly connecting an unloading conduit to the depending discharge pipe of a tank car or the like; a vehicle comprising a vehicle frame supported on wheels on a transverse axis and comprising frame portions forwardly and rearwardly of the axis; the forward frame portion comprising a generally horizontal plate element provided with a perforation therein; a generally upright upwardly open conduit telescoped through the perforation and having on its upper open end an enlargement; annular gasket means surrounding the conduit end opening and supported by the enlargement; a spring abutting upon the plate element and upon the enlargement and downwardly yieldingly supporting the conduit; the perforation being larger than the conduit to allow limited universal movement of the conduit therein; a lateral conduit extension below the perforation; the frame being rockable on the wheel axis upon depression of the rearward portion, to elevate the forward portion, to first engage the gasket beams with the end of the car discharge pipe and then tension the spring and effect sealing engagement of the gasket means with the enlargement and with the discharge pipe end.

6. In a device for sealingly connecting an unloading conduit to the depending discharge pipe of a tank car or the like; a vehicle comprising a

vehicle frame supported on wheels on a transverse axis and comprising frame portions forwardly and rearwardly of the axis; the forward frame portion comprising a generally horizontal plate element provided with a perforation therein; a generally upright upwardly open conduit telescoped through the perforation and having on its upper open end an enlargement; annular gasket means surrounding the conduit end opening and supported by the enlargement; a spring abutting upon the plate element and upon the enlargement and downwardly yieldingly supporting the conduit; the perforation being larger than the conduit to allow limited universal movement of the conduit therein; a lateral conduit extension below the perforation; the frame being rockable on the wheel axis upon depression of the rearward portion, to elevate the forward portion, to first engage the gasket means with the end of the car discharge pipe and then tension the spring and effect sealing engagement of the gasket means with the enlargement and with the discharge pipe end, a strut element and means for attaching it to the car to depend therefrom; mutually engageable projection and recess means on the strut element and on the rearward frame portion for holding the latter in depressed position.

7. In a device for sealingly connecting an unloading conduit to the depending discharge pipe of a tank car or the like; a vehicle comprising a vehicle frame supported on wheels on a transverse axis and comprising frame portions forwardly and rearwardly of the axis; the forward frame portion comprising a generally horizontal plate element provided with a perforation therein; a generally upright upwardly open conduit telescoped through the perforation and sealingly connected to the bottom of a bowl shaped receptacle and opening into its interior; compressible yieldable annular gasket material in the bowl on its bottom surrounding the conduit communicating opening; a coiled compression spring surrounding the conduit and abutting at its ends upon the plate element and bowl bottom, and supporting the conduit; the perforation being larger than the conduit to allow limited universal rocking movement of the conduit; a lateral conduit extension and a conduit controlling valve below the plate element; the frame being rockable on the wheel axis upon depression of the rearward portion to elevate the forward portion to first engage the gasket material with the end of the discharge pipe, and then compress the spring and effect sealing engagement of the gasket material with the pipe end and with the bowl bottom.

8. In a device for sealingly connecting an unloading conduit to the depending discharge pipe of a tank car or the like; a vehicle comprising a vehicle frame supported on wheels on a transverse axis and comprising frame portions forwardly and rearwardly of the axis; the forward frame portion comprising a generally horizontal plate element provided with a perforation therein; a generally upright upwardly open conduit telescoped through the perforation and sealingly connected to the bottom of a bowl shaped receptacle and opening into its interior; compressible yieldable annular gasket material in the bowl on its bottom surrounding the conduit communicating opening; a coiled compression spring surrounding the conduit and abutting at its ends upon the plate element and bowl bottom, and

supporting the conduit; the perforation being larger than the conduit to allow limited universal rocking movement of the conduit; a lateral conduit extension and a conduit controlling valve below the plate element; the frame being rockable on the wheel axis upon depression of the rearward portion to elevate the forward portion to first engage the gasket material with the end of the discharge pipe, and then compress the spring and effect sealing engagement of the gasket material with the pipe end and with the bowl bottom; an elongated depending strut element, and a quick detachable device for hingingly connecting an upper end portion thereof to a portion of the car above the rearward portion of the vehicle frame; and mutually engageable projection and recess means on the strut element and frame rearward portions for holding the latter depressed.

9. In a device for sealingly connecting an unloading conduit to the depending discharge pipe of a tank car or the like; a vehicle comprising a vehicle frame supported on wheels on a transverse axis and comprising frame portions forwardly and rearwardly of the axis; unloading conduit means comprising a generally upright

upwardly open conduit mounted on the forward portion of the frame; annular sealing means at the open upper end of the conduit in sealing relation to the conduit upper end; the conduit having a lateral extension below its upper end; the forward frame portion being rockable upwardly around the wheel axis to elevate the conduit and press the sealing means into sealing engagement with the end of the car discharge pipe upon depression of the rearward portion of the frame.
